UNITED STATES PATENT OFFICE

92,831

DESIGN FOR A NIGHT LIGHT

Herbert B. Tyler, Oak Park, Ill., assignor to Hamilton Beach Manufacturing Company, Racine, Wis., a corporation of Wisconsin

Application October 14, 1933, Serial No. 49,483

Term of patent 7 years

To all whom it may concern:

Be it known that I, HERBERT B. TYLER, a citizen of the United States, residing at Oak Park, in the county of Cook and State of Illinois, have invented a new, original, and ornamental Design for a Night Light, of which the following is a specification, reference being had to the accompanying drawing forming a part thereof.

The drawing is a perspective of a night light embodying the new design.

I claim:

The ornamental design for a night light substantially as shown.

HERBERT B. TYLER.
